MANUFACTURE OF REINFORCED HOLLOW STRUCTURES

Stelio Macerata, Johannesburg, Transvaal,
Union of South Africa

Application July 18, 1947, Serial No. 761,930
In the Union of South Africa August 12, 1946

10 Claims. (Cl. 25—154)

1

This invention relates to a method of manufacturing hollow structures, and to structures produced by such method. The invention is particularly applicable to the manufacture of tanks, silos, bins, towers (such as cooling towers), hoppers, chimneys, domes and the like.

The main object of this invention is to enable the application to such structures of the Hoyer method of reinforcement by means of pre-stressed wires.

A method according to this invention comprises the steps of so arranging a reinforcing wire that it has, in plan, the shape of an open or closed figure having a plurality of straight sides (such as a polygon) the direction of the wire being, except at the free ends of such wire where the direction may or may not be reversed, so reversed at each corner of the figure that the wire has, at each such corner, a loop projecting beyond that cross-section of the intended hollow structure at which such loop is located; tensioning said wire by application of suitable tensioning means at its free end or ends and possibly also at one or more of said loops; casting or otherwise moulding the structure so that the sides of the wire figure are partly embedded therein and so that said loops or parts thereof project from said structure; allowing the moulded material to harden to the required extent; and then preferably cutting off or otherwise removing said projecting wire loops.

Generally, the wire will have the shape of a spiral which is polygonal in plan and which may extend along the whole or part of the height of the structure that is to be erected and one or more such spirals may be incorporated in each structure. In some cases it is preferable so to incorporate in some part of the structure two or more polygonal spirals that each side of each spiral crosses, at least in plan, at least one side of at least one other wire spiral. When two or more polygonal wire spirals are provided within the same length of the longitudinal section of the structure, the corresponding sides of the wire polygons are preferably differently or oppositely inclined with respect to the longitudinal axis of the structure and are thus also inclined with respect to one another. In this manner, it is possible to reinforce the structure in two, preferably opposite, directions.

When the projecting loops are cut off, they leave all the sections of the wire or wires which remain within the shell of the structure pre-tensioned to the desired degree.

In a preferred form of carrying out the inven-

tion, the guiding means at each, except one, corner of the wire figure comprises a fixed sheave or a pair of fixed sheaves, whilst at said one corner there is provided a tensioning means which comprises the combination of a fixed sheave with a movable sheave, which is constrained for movement along a fixed rail and with means, which may be operated by a hydraulic jack, for forcing said movable sheave in the direction away from said fixed sheave.

If the hollow structure which is to be erected is polygonal in plan, at least one reinforcing wire is preferably so arranged that all the loops of that wire are formed at the corners of said structure and so that each side of the polygonal structure has a length of the reinforcing wire extending throughout the whole length of such side.

If, on the other hand, the hollow structure is round, each reinforcing wire will be arranged, in plan, in the form of an eight- or more-sided polygon so that a substantial part of the length of each side of such polygon will be embedded in the shell of the structure when the latter has been completed.

25 The invention will be further described with reference to the accompanying drawings, in which:

Figure 1 is a plan section of a reinforced polygonal structure.

Figure 2 is a part of a plan section of a round reinforced hollow structure.

Figure 3 is a diagrammatic view of a polygonal structure the walls of which are reinforced in several directions.

35 With reference to Figure 1, 2 and 3 indicate two parallel reinforcing wires and 4 indicates the polygonal structure which is to be erected.

Each of the wires 2, 3 is so guided at each of the corners 5, 6, 7, 8, 9 of the structure 4 about two stationary sheaves 10, 10 that each wire forms, in plan, a polygon a substantial part of the length of each of the sides of which extends within the plan of one of the walls of said polygonal structure so that the latter, when erected, has a length of each reinforcing wire extending throughout the whole length of each of its sides.

40 At the corner 11, each wire is guided about a stationary sheave 12 and about a movable sheave 13, which is constrained for movement along a fixed rail 14. 15 indicates a means, which may be operated by a hydraulic jack, for forcing said movable sheave 13 in the direction away from said fixed sheave 12.

45 In carrying out the invention, first a scaffolding 55 16 is erected to which the sheaves are secured in

the required positions, and the tensioning means 15 including the hydraulic jack or winch is brought into its operative relationship with respect to the sheaves.

Thereupon the reinforcing wires 2, 3 are put on, and are pre-tensioned to the required degree by operation of said tensioning means. Finally, shuttering is erected and the structure 4 itself formed from cementitious material.

The structure 4 may be formed by spraying, in which case essentially only internal shuttering is required, or it may be formed by casting, preferably with the use of vibrators, in which case internal and external shuttering walls will be erected from which the loops 17 of pre-tensioned wire project at the corners.

After the cementitious material has sufficiently solidified, the shuttering is removed and the wire loops 17 are cut off leaving the completed structure in which all sections of the reinforcing wire are under tension, thus producing the required degree of compressive stress in the whole shell of the structure.

Instead of or in addition to the wires 2, 3, a reinforcing wire 18 may be provided which is guided about fixed sheaves 19. The one end 20 of said wire 18 may be fixed and the other end, 21, will be tensioned by suitable means which are not shown in the figure.

In the arrangement of Figure 2, the structure 22 which is to be erected is circular, and the two reinforcing rods or wires 23 are so arranged that they form, in plan, two polygonal figures the sides of which cross one another in the same manner as do the lines of a star of David. The direction of the wires is reversed at the stationary sheaves 24 so that portions 25 of each wire extend within the plan of the structure while wire loops project beyond the plan of said structure. The ends 26 of the wires are fixed as by being anchored to the scaffolding, and the ends 27 are tensioned by suitable means. After the structure 22 has been formed from cementitious material, the wire loops 28 projecting from said structure are preferably cut off.

As shown in Figure 3, the reinforcing wires which, in plan, appear as polygonal figures, are preferably arranged in the form of spirals. In Figure 3, two groups 29, 30 of wires are shown which reinforce respectively the sides 31, 32, 33, 34, 35, 36 and the sides 31, 37, 33, 34, 38 and 36 of the structure.

Each group of wires forms, during the manufacture of the structure, at each of the corners from which said wires are shown to extend, a series of loops which project beyond said corners, said loops being cut off after the completion of the structure leaving the wires 29, 30, pre-tensioned to the desired degree.

I claim:

1. A method of manufacturing hollow structures comprising the steps of bending a reinforcing wire to the shape of a figure which, in plan, has a plurality of straight sides, the direction of the wire being so reversed at each corner of the figure that the wire has, at each such corner, a loop projecting beyond that cross-section of the intended hollow structure at which such loop is located whereby to provide a sharp intersection of the reinforcing wire at each corner; tensioning said wire by application of suitable means; applying cementitious material to

the wire so that the sides of the wire figure are partly embedded therein and so that at least parts of said loops project from said material; and allowing the cementitious material to harden until it forms the hollow structure.

2. A method as claimed in claim 1, comprising the steps of removing such parts of the wire as project from the set cementitious structure.

3. A method as claimed in claim 1, in which the wire is bent to form a spiral which is polygonal in plan and which extends along the whole of the height of the structure that is to be erected.

4. A method as claimed in claim 1, in which the wire is bent to form a spiral which is polygonal in plan and which extends along part of the height of the structure that is to be erected.

5. A method as claimed in claim 1, in which a plurality of reinforcing wires is used.

6. A method as claimed in claim 1, in which at least two wires are used each of which is bent to the shape of a polygonal spiral, each side of each spiral crossing, at least in plan, at least one side of at least one other wire spiral.

7. A method as claimed in claim 1, in which at least two wires are used within the same length of the longitudinal section of the structure, each wire being bent to the shape of a polygonal spiral; the corresponding sides of the wire polygons being differently inclined with respect to the longitudinal axis of the structure and thus being also inclined with respect to one another.

8. A method as claimed in claim 1, for erecting polygonal structures in which at least one reinforcing wire is so arranged that all the loops of that wire are formed at the corners of said structure and so that each side of the polygonal structure has a length of the reinforcing wire extending throughout the whole length of such side.

9. A method as claimed in claim 1, for erecting circular structures, in which at least one reinforcing wire is bent to a figure which, in plan, has the shape of a polygon having at least six sides, a substantial part of the length of each side of such polygon being arranged within the plan, at the corresponding section, of the shell of the structure that is to be erected.

10. A method of manufacturing hollow structures comprising the steps of erecting scaffolding, fixing to said scaffolding a series of sheaves spirally arranged; placing a reinforcing wire so that the direction of the latter is reversed to form a loop around some of said sheaves; tensioning said wire; erecting shuttering so that parts of the prestressed wire are within an area determined by said shuttering while said sheaves are outside said area; placing cementitious material within such shuttering; allowing said material to harden; and removing said scaffolding, said sheaves and said shuttering.
